UNITED STATES PATENT OFFICE

134,824

DESIGN FOR A BADGE OR SIMILAR ARTICLE

Douglas Freese, Portage Des Sioux, Mo.

Application April 3, 1942, Serial No. 106,443

Term of patent 3½ years

To all whom it may concern:

Be it known that I, Douglas Freese, a citizen of the United States, residing at Portage des Sioux, in the county of Saint Charles and State of Missouri, have invented a new, original, and ornamental Design for a Badge or Similar Article, of which the following is a specification: reference being had to the accompanying drawing, forming a part thereof.

The figures shown in the drawing are fanciful and are not intended to represent any person living or dead.

I claim:

The ornamental design for a badge or similar article, as shown and described.

DOUGLAS FREESE.
